REGENERATIVE TELEGRAPH REPEATERS

Arthur Edward Brewster, London, England, assignor to International Standard Electric Corporation, New York, N. Y., a corporation of Delaware

Application March 23, 1955, Serial No. 496,276

Claims priority, application Great Britain April 6, 1954

10 Claims. (Cl. 178—70)

The present invention relates to electric telegraph regenerative repeaters of the kind which does not employ mechanical devices for regenerating the telegraph signals.

In recent years a number of regenerative repeaters have been proposed, in which the regeneration is carried out by means of static electric switches such as thermionic valves or gas-filled tubes. For example a regenerative repeater for a start-stop printing telegraph system employing gas-filled counting and other tubes is described in British patent specification No. 692,411. In addition to regenerating the signal code combinations this repeater is made unresponsive to false start signals such as may be produced by interference, particularly in radio systems, and furthermore includes means for preventing confusion due to an abnormally short stop signal which may result from interference or distortion. A synchronous start-stop repeater employing gas-filled tubes in which code combinations are transmitted at precisely regular intervals (e. g. from perforated tape) is described in U. S. Patent No. 2,749,386. This repeater includes means for dealing with the particular problems set by the timing errors of the start and stop transitions.

The recent development of semiconductor amplifiers (crystal triodes), which have proved to be particularly suitable for use as trigger devices, has opened up the possibility of making economies in the design and operation of telegraph regenerative repeaters, as a result of the small size of crystal triodes, and the low currents and voltages required for their operation.

The invention accordingly provides an electric telegraph regenerative repeater for telegraph signal combinations consisting of marking and spacing signal elements, comprising a plurality of crystal triode trigger devices arranged in a counting chain, means for periodically triggering the said trigger devices in order to produce regularly repeated triggering pulses for timing the intervals occupied by the elements of a signal combination, conditioning means jointly controlled by the said pulses and by the received signal for conditioning a transmitting device to transmit a signal element of the same kind (marking or spacing) as the corresponding received element, and means for holding the said transmitting device in a condition to transmit a signal element of one kind until re-conditioned to transmit a signal element of the opposite kind.

The invention further provides an electric telegraph regenerative repeater for start-stop code combinations of signal elements comprising a master oscillator, a crystal triode counter device controlled thereby for generating a train of short timing pulses having a repetition period equal to a signal element period said counter device being normally inoperative, starting means operated in response to a start transition for rendering said counter device operative, terminating means operative upon the lapse from the commencement of a retransmitted start element of a period at least equal to the combined durations of

said start element and the code combination immediately following for rendering said counter device again inoperative, and a flip-flop device for retransmitting the received signal elements under control of said timing pulses.

5 The invention will be described with reference to the accompanying drawings, in which:

Fig. 1 shows a block schematic circuit diagram of an example of a telegraph regenerative repeater according to the invention;

10 Fig. 2 shows graphical diagrams used to explain the operation of the repeater, and

Figs. 3 to 7 show examples of circuit details of the block elements of Fig. 1.

15 The invention will be illustrated by an embodiment comprising a regenerative repeater for a teleprinter start stop system of the usual type, and providing facilities similar to those provided by the repeater described in British Patent No. 692,411 already referred to. It will be understood, however, that the invention is also applicable to other systems employing a binary (mark-space) code, such as that covered by said U. S. Patent 2,749,386 already referred to, or a Baudot multiplex system.

25 The telegraph regenerative repeater circuit shown in Fig. 1 is intended for a teleprinter start-stop five-element code operating at a speed of 50 bauds. Only minor modifications which will be obvious to those skilled in the art, will be necessary to adapt the circuit for a code with a different number of elements or for a different speed.

30 For clearness it will be explained that a start-stop signal element code combination consists of a number of equal fixed periods during which the telegraph circuit can be in the marking or spacing condition. Each such period or condition is called a "signal element," and 35 the fixed period is called the "element period." The group commences with a start transition from the idle or waiting condition to the opposite condition, and the first element period following the start transition is called the "start" period or element. Every two adjacent signal 40 elements of opposite kind (mark or space) are separated by a transition. The group is terminated by the stop transition to the idle or waiting condition. In the case of a five element code, the combination consists of a start element followed by five code elements, and when 45 undistorted these six elements are of the same duration (20 milliseconds for a speed of 50 bauds). The period after the stop transition, which lasts until the next start transition, is of variable duration and is called the "stop" 50 element or period. Generally the minimum duration of the stop element is one element period, but in some systems it is 1½ element periods (30 milliseconds).

55 It will be assumed that when the telegraph connection is complete and ready for transmitting signals, the idle or waiting condition is the marking condition. It should be mentioned, however, that in some telegraph exchange systems a permanent spacing condition may exist before the line is seized at the exchange, the normal idle or marking condition being resumed after the line has been seized. 60 This special unseized condition is dealt with in the circuit of Fig. 1 in a manner which will be explained later, and it will for the present be assumed that the normal idle condition of the circuit is the marking condition.

In order to make the invention clear, certain particular 65 values, such as voltages and times, will be assumed in the description which follows, but it will be understood that these values are not essential and other values could be used, according to circumstance.

70 The distorted telegraph signals representing a code group are applied in some suitable way not indicated to a receiving relay 1, the contacts of which are in the position shown for the marking condition. The fixed

contacts are respectively connected to two conductors 2, 3 a designated mark and space. These conductors are connected to a trigger pulse generator 4, to which is connected a direct current source 5 having its positive terminal connected to ground, and having a potential of 15 volts. In the marking condition, the relay 1 connects the mark conductor 2 to ground, and the circuit of the trigger pulse generator 4 is such that the space conductor 3 is at a negative potential of about 15 volts. When the relay 1 changes over to the spacing condition, the potentials of the conductors 2 and 3 are interchanged, and at the same time, the generator 4 produces a short positive output trigger pulse which it applies to conductor 6. A similar trigger pulse is produced every time the relay 1 changes over in either direction.

The regenerated signals are supplied to an output conductor 7 from a transmitting relay 8 controlled by a pair of bi-stable two-condition trigger devices 9, 10 which are interconnected in such a way that they form an arrangement similar to a flip-flop circuit, so that they are always in opposite conditions. The triggering of the flip-flop devices 9, 10 is timed by short timing pulses, according to the condition of conductors 2 and 3, as will be explained later. In the position shown, the relay 8 applies a negative marking potential to the conductor 7.

The timing of the whole circuit is controlled by a master oscillator 11 connected to a chain of counter circuits 12, 13, 14. The oscillator 11 should preferably be crystal controlled, and in the present example generates sine-waves having a stable frequency of 5.4 kilocycles per second. The counters 12, 13 and 14 divide respectively by 54, 2 and 6, and each may consist of any convenient number of dividing stages. Preferably these counters are of the kind described in the specification of my co-pending patent, Serial No. 433,397, filed June 1, 1954, and the counters 12 and 13 together may consist of three stages each dividing by three, and two stages each dividing by two, like those shown in Fig. 9 of the last-mentioned specification (with a slight modification to be explained later). Similarly the counter 14 may consist of two such slightly modified stages dividing respectively by three and two.

The counters 12 and 14 are controlled by two corresponding bi-stable two-condition trigger devices 15, 16 which will be respectively called the primary and secondary reset devices. Briefly, their function is to prevent the counters from operating until the arrival of a start transition, and to block and restore the counters to a standard condition after the stop transition. Their action will be explained more fully later on.

The counter 13 is controlled by a two-condition trigger device 17, called the false start reset device. The action of device 17 is slightly different from that of devices 15 and 16 in that its function is to restore the counter 13 quickly to the normal or standard condition without at the same time blocking it.

A monostable two-condition trigger circuit 18, called the short stop corrector, is provided to prevent the operation of the reset device 15 if a fresh start transition is received too quickly after a stop transition as will be explained later.

When the counters 12 and 13 are operating, the counter 13 generates short positive timing pulses at 20 millisecond intervals which control the operation of the flip-flop devices 9 and 10 as already mentioned.

In order to make the arrangements clear, it will be stated that all the trigger devices 9, 10 and 15 to 18 comprise crystal triodes which can assume a blocked condition (the "off" condition) in which the emitter and collector currents are small or zero, or an unblocked condition (the "on" condition) in which the emitter and collector currents have moderate values. In the normal idle (marking) condition of the regenerative repeater, all the said trigger devices except 9 are "on." The application of a positive triggering pulse will trigger any

such circuit from "on" to "off," while the application of a negative triggering pulse will trigger any bi-stable device from "off" to "on." The reset devices 15 and 16, when "on," apply negative potentials of 15 volts respectively to the counters 12 and 14, which prevent them from operating. When either of these devices is triggered "off," the applied negative potential is changed to about 3 volts, and the counters will then be released, and can operate.

10 When the relay 1 is in the marking condition, the mark conductor has zero potential applied to it, which blocks the flip-flop device 10, and the secondary reset device 16, so that they cannot be triggered "off."

When the relay 1 is in the spacing condition, the space conductor has zero potential applied to it, which blocks the flip-flop device 9, and also blocks or shuts a gating circuit 19 (called a gate) through which (when unblocked or open) a negative pulse is applied from the counter 13 to trigger the primary reset device 15 "on." A separate blocking potential is also applied to the gate 19 from the secondary reset device 16 when it is triggered "off." Thus a triggering pulse can only reach the primary reset device 15 from the counter 13 through the gate 19 if the relay 1 is in the marking condition and if at the same time the secondary reset device 16 is "off."

The flip-flop devices 9 and 10 are so arranged that a positive timing pulse from the counter 13 will trigger "off" whichever of the devices 9 and 10 happens to be "on," provided that it is not blocked over conductor 3 or 2. Furthermore, devices 9 and 10 are connected by a conductor 20 in such a manner that whenever one of the devices 9 or 10 is triggered "off," it triggers the other one "on" over conductor 20. By this means, the marking or spacing condition of the flip-flop devices 9 and 10 is only reversed by a particular timing pulse if after the arrival of the preceding timing pulse the relay 1 has changed over.

The short stop corrector 18 (which, as already stated, is normally "on") when triggered "off" by a positive pulse 40 from the counter 14 after the whole of a code combination has been received, applies a blocking pulse to the primary reset device 15 which lasts until the device 18 has restored itself to "off." This blocking pulse prevents the reset device 15 from being triggered "on" if a new 45 start signal arrives too soon. This will be explained more fully later.

When the primary reset device 15 is triggered from "off" to "on," it supplies a short negative triggering pulse over conductor 21 to trigger "off" the false start reset 50 device 17, which then supplies a short resetting pulse to restore the counter 13 quickly to normal.

In Fig. 1, conductors which supply triggering pulses are provided with single arrow-heads, and the designation "off" or "on" is added to signify which way the corresponding device is triggered by the pulse. Conductors which supply controlling potentials or pulses are provided with double arrow-heads.

The operation of the circuit will now be described. It will be assumed that the circuit is in the idle or marking condition, and that a code group representing a teletypewriter character is received. On receipt of the start transition at zero time the relay 1 changes over and puts ground potential on the space conductor 3, conductor 2 then acquiring a potential of -15 volts. A positive trigger pulse from the generator 4 triggers the primary reset device 15 to "off." This releases the counter 12 which starts operating, and at 10 milliseconds supplies a triggering pulse to the counter 13, which on being triggered generates the first timing pulse (at 10 milliseconds), 65 which is supplied to the flip-flop devices 9 and 10. Device 10 being now no longer blocked, will be triggered "off" by the timing pulse, device 9 being triggered "on" at the same time over conductor 20. Relay 8 is therefore 70 changed over and applies a positive spacing potential to the output conductor 7.

The timing pulse is also applied to the secondary reset device 16, which is accordingly triggered "off," thus releasing the counter 14, and blocking the gate 19.

The counting chain consisting of elements 11, 12 and 13 then continues to operate, and a regular series of timing pulses at 20 millisecond intervals is applied to the devices 9 and 10. As already stated, the first timing pulse is generated by the counter 13 at the moment when it is first triggered by a pulse from the counter 12, that is at 10 milliseconds after zero time. Timing pulses then follow at 30, 50, 70, 90, 110 and 130 milliseconds.

Thus 10 milliseconds after the receipt of the start signal, the flip-flop devices 9 and 10 will be changed over by the first timing pulse, and will operate the relay 8 to space. Any subsequent timing pulse will reverse or not reverse, the condition of the flip-flop devices 9 and 10 depending upon the conditions of the conductors 2 and 3 at that time. Thus it will be seen that the start transition of the regenerated code group is delayed by 10 milliseconds after the start transition of the received code group, and all the subsequent transitions are delayed by the same amount after the corresponding signals of the received code group if the signals are undistorted. It will be understood that once the primary reset device 15 has been triggered "off" by the starting trigger pulse from the generator 4, subsequent trigger pulses resulting from the operation of relay 1 will have no further effect.

The operation of the circuit will be more clearly understood from a particular case illustrated in Fig. 2. All the graphs are shown with reference to the same time scale, the zero of which corresponds to the time of arrival of the start transition of a typical code signal group shown undistorted by graph A. This group has mark-to-space transitions at 0 (the start), 60 and 100 milliseconds, and space-to-mark transitions at 20 and 120 (the stop) milliseconds.

Graph B shows an example of the manner in which the signal group of graph A may actually arrive in distorted form. Graph B indicates the operations of the moving contact spring of the relay 1 (Fig. 1) and not the received waveform applied to the relay 1, which will usually be of a rounded and irregular character. In graph B some of the transitions after the start transition are too early and some too late. Graph C shows the timing pulses applied to the flip-flop devices 9 and 10 (Fig. 1). Graph D shows the regenerated signal group and indicates the operations of the moving contact spring of the relay 8 (Fig. 1).

From graph B it will be seen that the first space-to-mark transition 22 after the start is at 12 milliseconds (8 milliseconds early). As already explained, the counters 12, 13 and 14 (Fig. 1) are started in response to the start transition at zero time, and the first timing pulse 23 changes over the flip-flop devices 9 and 10 and the relay 8 (Fig. 1) to space, thus producing the regenerated start transition 24 (graph D) at 10 milliseconds. On the arrival of the second timing pulse 25, the flip-flop devices 9 and 10 and the relay 8 are changed back to mark as shown at 26, graph D, because of the change to mark in the received group, graph B, at 22, which occurred during the 20 millisecond period before the pulse 25. The next timing pulse 27 has no effect because there is no change in graph B during the period 30 to 50 milliseconds, so that the mark conductor 2 (Fig. 1) is at earth potential and blocks the flip-flop device 10, thus preventing the pulses 27 from having any effect, as already explained. The next timing pulse 28 arrives after the transition 29 to space in graph B, and therefore it can operate the flip-flop devices 9 and 10 and the relay 8 (Fig. 1) to produce the corresponding transition 30 at 70 milliseconds shown in graph D. It will be clear that the next two timing pulses 31 and 32 will produce transitions 33 and 34 in graph D corresponding to the transitions 35 and 36 in graph B.

The last space-to-mark transition 37 of graph B is the

stop transition. This is shown about 5 milliseconds late, and the seventh timing pulse 38 produces a correctly timed transition 39, graph D, at 130 milliseconds. It will be seen that the transitions of graph D are all correctly spaced in time, but are 10 milliseconds later than the corresponding transitions of graph A.

Referring to Fig. 1, the counter 14 counts six periods of 20 milliseconds after the first timing pulse (23, Fig. 2) produced by the counter 13, and then generates a negative stopping pulse at 130 milliseconds which is applied over conductor 40 to trigger the reset devices 15 and 16 back to "on," thus blocking and restoring to normal counters 12 and 14. The false start reset device 17 is at the same time triggered "off" by a pulse from the primary reset device 15 over conductor 21, as already explained, and restores the counter 13 quickly to the standard condition. The circuit is now back to normal and ready to receive another code combination, which it deals with in the manner described.

It is necessary now to explain the operation of the short stop corrector 18. It has already been explained that in the case of teleprinter devices it is necessary that the stop period should be long enough to ensure that the mechanism comes to rest after dealing with a code group, before it can be operated again to deal with the next code group.

It is necessary therefore that the circuit of Fig. 1 should not operate if the received stop period is too short, in order to avoid mutilating the characters. At the same time as the counter 14 delivers a negative stop pulse over conductor 40, it also delivers a short positive pulse 41 (graph E, Fig. 2) over conductor 42, which triggers the short stop corrector 18 "off." This device then generates a rectangular blocking pulse 43 (graph E, Fig. 2) the duration of which can be adjusted between limits of, say 8 and 18 milliseconds (as indicated by the dotted lines in graph E) and applies this pulse to block the primary reset device 15 so it cannot be triggered "off" by any pulse arriving over conductor 6 until the blocking pulse 43 has terminated. Thus, for example, suppose that the duration of the blocking pulse 43 is adjusted to 15 milliseconds. Then a fresh start transition 44 (graph B, Fig. 2) can have no effect on the circuit unless it arrives after 145 milliseconds. On account of the 10 milliseconds delay in the transmission of the regenerated code group, the regenerated start transition 45 (graph D) cannot then occur before 155 milliseconds, which means that the duration of the regenerated stop signal cannot be less than 25 milliseconds. Providing that the new start transition 44 is allowed to trigger off the device 15 at the end of the blocking period of 15 milliseconds the first timing pulse 46 (graph C, Fig. 2), corresponding to the fresh start is 25 milliseconds after the last timing pulse 38 of the previous code group. It will be understood that by adjusting the duration of the pulse 43, the minimum duration of the stop period between the transitions 39 and 45 can be set as desired.

It is desirable that the circuit of Fig. 1 should not respond to false start signals, that is, to start conditions lasting for less than 10 milliseconds, which may be due to interference or other accidental causes. The gate 19 and its connections are provided for this purpose. Suppose, for example, that a false start condition of duration about 7 milliseconds is received. The return to the marking condition at 7 milliseconds is indicated by the dotted line 22A in graph B.

As already explained, the start transition at zero time switches "off" the primary reset device 15, which allows the counter 12 to start operating. At 10 milliseconds the counter 13 generates the timing pulse 23 (graph C, Fig. 2), but since owing to the transition 22A at 7 milliseconds the circuit is back in the marking condition, the flip-flop device 10 is blocked, and so the timing pulse has no effect. Further, the secondary reset device 16 is

also blocked and cannot be triggered by the timing pulse. The gate 19 is now unblocked (or open) because it receives no blocking potential either from the conductor 3 or from the device 16, which is "on." Thus a negative pulse generated by the counter 13 at the same time as the timing pulse 23 can now pass through the gate 19 and trigger the primary reset device 15 back again to "on." When device 15 is triggered to "on" it generates a short pulse over conductor 21 which operates the false start reset device 17 to "off" thereby restoring to normal counter 13. The restoration of the device 15 to "on" also blocks and restores the counter 12. The circuit is therefore again in the normal condition without having produced any output transition corresponding to the false start transition. It will be noted that the gate 19 is unblocked only during the period between the transitions 22A and 22 (graph B, Fig. 2).

The repeater of Fig. 1 also deals with the permanent space condition. After the transmission of a series of characters, the repeater resumes the normal idle condition with the contacts of the relays 1 and 8 in the position shown, and the counters 12, 13 and 14 are all blocked and inoperative. Now, if the circuit is broken down at the exchange, so that a permanent spacing condition is produced, the relay 1 changes over to space and the repeater operates as described, as though all the code elements were spacing elements. Relay 8 will accordingly be changed over to space. However, at 130 milliseconds after the transition to the permanent spacing condition, the counter 14 applies the negative stop pulse over conductor 40 to switch "on" the reset devices 15 and 16 as already described, whereupon the counters 12, 13 and 14 are all stopped. The repeater now waits in the spacing condition until the telegraph circuit is seized again, whereupon a marking condition is produced and the relay 1 changes over to mark. This causes the generator 4 to generate a trigger pulse which starts up the counters 12 and 13, as before, and the repeater circuit behaves in the manner described for the false start condition, except that, since the flip-flop devices 9 and 10 are in this case in the spacing condition, the first timing pulse from the counter 13 is able to change them over to mark. The gate 19 is open to allow the primary reset device 15 to be switched back to "on" at 10 milliseconds because the secondary reset device 16 is held blocked in the "on" condition, and the repeater circuit is again in the normal idle (or marking) condition ready to accept a series of code signals as already described. It will be seen that the space-to-mark transition which occurred on the seizure of the telegraph circuit is transmitted to the output line 7 after the standard delay of 10 milliseconds.

Although in Fig. 1 the relays 1 and 8 are shown for clearness as conventional electro-mechanical telegraph relays, it will be understood that any suitable form of circuit which carries out equivalent functions, by means of electronic devices will preferably be used.

Details of the trigger pulse generator 4 are shown in Fig. 3. It comprises a resistor 47 having one terminal connected to the negative terminal of the direct current source 5 (also shown in Fig. 1) and the other terminal connected to the output conductor 6, and to the mark and space conductors 2 and 3 respectively through two identical circuits comprising resistors 48, 49 and resistors 50, 51 equal in resistance value respectively to resistors 48 and 49. Resistors 48 and 50 are shunted by equal capacitors 52 and 53. The contacts of relay 1 are shown connected to conductors 2, 3 and to ground, as in Fig. 1.

With the moving spring of the relay 1 in the marking condition shown, the source 5 is connected across the series connection of resistors 47, 48 and 49, and the capacitor 52 is charged, and the capacitor 53 is discharged. The potential of the conductor 6 is

where R_1 , R_2 and R_3 are the resistances of resistors 47, 48 and 49 respectively, and V is the potential of the source 5 (15 volts). The conductor 2 is at ground potential, and the conductor 3 is a negative potential of 5 V , since substantially no current flows in conductor 3 in this condition. When the relay 1 changes over to the spacing condition, conductor 3 is connected to ground, and since capacitor 53 is uncharged, it effectively short-circuits the resistor 50 at first, so that the potential of the conductor 6 is initially $-VR_3(R_1+R_3)$, which however returns exponentially to the value

$$-V(R_2+R_3)/(R_1+R_2+R_3)$$

as the capacitor 53 charges up. A substantially instantaneous positive change in the potential of the conductor 6 thus occurs, and this will for convenience be called a positive pulse, though the actual potential of the conductor 6 is always negative. The duration of the trigger pulse so generated depends on the time constant of the charging circuit of the capacitor 53 which should be selected to be sufficiently short (for example 0.1 and 1 millisecond). Meanwhile the capacitor 52 will have discharged, and when the relay 1 changes back again to the marking condition the process is repeated and another short positive trigger pulse is generated.

Fig. 4 shows details of the elements 11, 12, 13 and 17 of Fig. 1. The oscillator 11 comprises a crystal triode 54 having an emitter electrode 55 shown with an arrow-head, a collector electrode 56 shown without an arrow-head, and a base electrode shown as a plate 57. All crystal triodes in the circuits to be described below will be shown in the same way, and it will not therefore be necessary to designate the electrode in future. The frequency is determined by a piezo-electric crystal 58 connecting the emitter and collector electrodes, and tuned to 5.4 kilocycles per second. The base electrode 57 is connected to ground, and the emitter and collector electrodes 55, 56 are connected to ground through parallel resonant circuits 59, 60 tuned to the same frequency as the crystal 58. The emitter electrode is connected to a tapping point on the inductor of the resonant circuit 59 in order to match the rather low impedance of the emitter circuit to the series resonance impedance of the crystal, which is rather high on account of the low resonance frequency. The emitter electrode is polarised from a positive direct current source 61, having a potential of 150 volts, through a resistor 62. The collector electrode is likewise polarised from a negative direct current source 63, having a potential of 15 volts, through a resistor 64.

Further details of the oscillator will be found in the specification of the co-pending patent application of A. E. Brewster and P. E. Graham, filed February 10, 1955, and bearing Serial No. 487,412.

The counters 12 and 13 of Fig. 1 comprise five counting stages as shown in Fig. 4 consisting of crystal triodes 65 to 69. These are arranged in substantially the same manner as the four counting stages illustrated in Fig. 9 of the specification of my co-pending application No. 433,397, with one additional intermediate stage, except that the holding rectifiers 72 to 75 of the first four stages are connected to a common control conductor 76, which comes from the primary reset device 15 of Fig. 1, instead of the negative end of a voltage source. The holding rectifier 70 of the last stage 69, is, however, connected as described in the last-mentioned specification to a 3-volt negative source 71. The first three stages 65 to 67 are each designed to divide by 3, while the stages 68 and 69 divide by 2. The operation of these counting stages is fully described in the prior specification just referred to, and it will be explained here that each stage is normally in the "off" condition with the emitter electrode negative to the base electrode. When the primary reset device 15 (Fig. 1) is "on," the emitter electrode of each of the stages 65 to 68 has a potential of -15 volts applied to it over conductor 76, so that the stage cannot be triggered,

$$-V(R_2+R_3)/(R_1+R_2+R_3)$$

and when the reset device 15 is triggered "off" the potential applied to conductor 76 is changed to -3 volts. This allows the potential of the emitter electrode to rise to -3 volts during a period determined by the time constant of the associated capacitor-resistor circuits, at which potential it is held by the corresponding rectifier. When the emitter potential has reached -3 volts the stage can be triggered by a pulse from the preceding stage, and then the emitter potential rapidly falls to -15 volts and it is again insensitive to triggering until the potential has risen to -3 volts. Thus by suitable choice of the time constant of the capacitor-resistor circuit, the stage can be made to respond only to every *n*th triggering pulse when it is desired to divide by *n*.

When any stage is triggered, the collector electrode generates a short positive output which is applied to the emitter electrode of the following stage.

The stage 69 differs from the other four stages only in that the initial potential of the emitter electrode is always -3 volts as determined by the source 71. It is therefore triggered by the first pulse from stage 68, while stages 65 to 68 are not triggered until the arrival of the *n*+1 pulse from the previous stage. Stage 69 is then subsequently triggered by every other pulse from stage 68.

The collector electrode 56 of the crystal triode 54 in the oscillator 11 is connected through a blocking capacitor 77 and a rectifier 78 to the base electrode of the crystal triode 65 in the first counting stage. A shunt resistor 79 connects the junction point of the elements 77 and 78 to ground.

The rectifier 78 is directed so that it will pass only the negative half-waves of the generated oscillations to the base electrode of the crystal triode 65 for triggering this counting stage.

The final output of short positive pulses spaced at 20 milliseconds intervals is taken from the output resistor 80 connected in series with the collector electrode of the crystal triode 69 in the last stage, which last stage corresponds to the counter 13 of Fig. 1. Positive pulses for triggering the counter 14 (Fig. 1) are supplied to an output conductor 81 connected to a tapping point on the resistor 80. Positive pulses of rather larger amplitude are supplied to an output conductor 82 connected to the upper end of resistor 80. These pulses are the timing pulses used for triggering the flip-flop devices 9 and 10 and for triggering "off" the secondary reset device 16 of Fig. 1. Since negative pulses are required for triggering "on" the primary reset device 15 of Fig. 1, a transformer 83 is provided in Fig. 4 with its primary winding connected across the output resistor 80, and with its secondary winding having one terminal connected to ground and the other connected to an output conductor 84 connected to the gate 19, Fig. 1, the transformer being so connected as to supply negative pulses to conductor 84.

In the case of the first stage 65, the capacitor 85 connected to the emitter electrode starts to charge up and the emitter potential slowly rises towards -3 volts. The first two negative-half waves after the triggering "off" of the reset device 15 are unable to trigger the first counter stage, but by the time of arrival of the third negative half wave, the potential of the emitter electrode has risen sufficiently to allow the stage to be triggered, whereupon its potential falls again to -15 volts and the process is repeated. Thus the first counter stage will be first triggered approximately three periods of the oscillator 11 after being released and then every third period thereafter. The other counter stages behave in like manner. When the primary reset device 15 is restored to "on," the potentials of all the emitter electrodes of the first four counting stages are taken to -15 volts and further counting stops.

It will thus be seen that when the primary reset device 15 (Fig. 1) is triggered "off," the fourth counter stage 68 will be first triggered after $54/5.4 = 10$ milliseconds, and will thereafter be triggered every 10 milliseconds.

The fifth counting stage 69, which corresponds to the counter 13, Fig. 1, is not affected by the primary reset device 15, and because its emitter electrode is normally held at -3 volts, it will be triggered by the first pulse generated by the stage 68, and thereafter every 20 milliseconds. In this it differs from any earlier stages which cannot be triggered by the first pulse from the preceding stage. Stage 69 is however reset by a trigger circuit comprising the crystal triode 86, which corresponds to the false start reset device 17, Fig. 1. The emitter and base electrodes of the crystal triode 86 are connected to the positive terminal of the source 61 through respective resistors 87 and 88, and the collector electrode is connected to the negative terminal of the source 63. The base electrode is connected through a rectifier 89 to a negative direct current source 90 whose potential is 3 volts. The rectifier 89 is connected so that it would be in the conducting condition if it were disconnected from the base electrode, and thus substantially prevents the potential of the base electrode from rising above -3 volts.

The emitter electrode is connected through a rectifier 91 to the tapping point of the load resistor 92 of the emitter electrode of the stage 69, to which tapping point the rectifier 70 is also connected. The input conductor 21 leading from the primary reset device 15 (Fig. 1) is connected to the emitter electrode of the stage 86 through a capacitor 93 and a rectifier 94, which should be directed so that it will pass negative pulses to the emitter electrode. A resistor 95 connects the junction point of elements 93 and 94 to the negative terminal of source 63. The capacitor 93 and resistor 95 act to differentiate the pulse generated by the device. The trailing edge differential pulse (which is negative) is passed to the emitter electrode by the rectifier 94.

The crystal triode 86 is normally "on," which means that moderate emitter and collector currents are flowing, so the three electrodes are all at potentials not much different from -15 volts. Rectifier 89 will be blocked in this condition, and rectifier 91 should be directed so that it is also blocked in this condition.

When a pulse arrives over conductor 21 from the primary reset device 15 (Fig. 1), the negative differential pulse will cut off the emitter and collector currents, and the potential of the base electrode will rise to the potential of the source 90 (-3 volts) because the rectifier 89 will now become unblocked by the current flowing through the resistor 88. As was explained above, the crystal triode 86 (which is the false start reset device 17 of Fig. 1) is triggered substantially at the same time as a pulse is generated by the stage 69 (counter 13 of Fig. 1), and so the potential of the emitter electrode of stage 69 will have just started rising from about -15 volts and so will still have a relatively large negative value. On the disappearance of the triggering pulse applied to conductor 21, the rectifier 91 becomes unblocked by the current through the resistor 87. The emitter electrode of the crystal triode 86 then assumes practically the same potential as that of the crystal triode 69 and thus remains blocked because the base potential has risen to -3 volts as already explained.

The unblocking of the rectifier 91 effectively connects the resistor 87 in parallel with the upper part of resistor 92, and accordingly the charging rate of the capacitor 96 is increased. By suitable choice of the resistance values it can be arranged so that the potential of the emitter electrode of the crystal triode 69 reaches the holding value of about -3 volts in less than 10 milliseconds instead of the usual 20 milliseconds. As soon as the holding value has been reached, the crystal triode 86 becomes unblocked and it resumes the "on" condition with the potentials of all electrodes at nearly -15 volts, the rectifiers 89 and 91 being then blocked.

It will be noted that since the frequency of the oscillator 11 is 5.4 kilocycles per second in the particular

example chosen, it is possible for the starting of the counter train to be nearly 0.2 millisecond late. This corresponds to a telegraph distortion of a little under 1% and will be good enough for most practical purposes. The error can be made as small as desired by suitably increasing the frequency of the oscillator 11, and by providing additional dividing stages (not shown) to the counter chain.

Fig. 5 shows the arrangement of the counter 14 of Fig. 1, which consists of two crystal triode stages 97, 98 dividing by 3 and 2, respectively, arranged substantially in the same way as the stages 67 and 68 of Fig. 4, but with an output transformer 99 arranged as in the case of stage 69 for producing negative output pulses. The two stages are controlled over conductor 100 from the secondary reset device 16 (Fig. 1) just in the same way as the four stages of Fig. 4 are controlled over conductor 76. Positive output pulses are supplied over conductor 42 from the upper end of the load resistor 101 to trigger "off" the short stop corrector 18 (Fig. 1) while negative output pulses are supplied over conductor 40 from the secondary winding of the output transformer 99 to trigger "on" the reset devices 15 and 16.

Fig. 6 shows circuit details of the primary reset device 15, the short stop corrector 18, and the gate 19 of Fig. 1. Since the circuit of the secondary reset device 16 is the same as that of the device 15, only the external connections being different, in Fig. 6 the connections for the secondary reset device 16 are indicated by the bracketed references.

The primary reset device 15 employs a triggering arrangement which is the subject of my co-pending Patent Application No. 495,993, filed March 22, 1955. It comprises a crystal triode 102, having the emitter and base electrodes connected to the positive terminal of the source 61 through respective resistors 103 and 104. The collector electrode is connected to conductor 6 which leads from the trigger pulse generator 4 (Fig. 1). Conductor 40 which leads from the counter 14 (Fig. 1) is connected to the base electrode through a rectifier 105 directed so that it will pass negative pulses to the base electrode. The base electrode is also connected over conductor 106 to the output of the gate 19, the circuit of which is shown in the dotted outline, and conductor 84 leading from the counter 13 (Fig. 1) is connected to the input of the gate. The output conductor 21 leading to the false start reset device 17 (Fig. 1) is connected to the base electrode.

The emitter electrode is connected through a rectifier 107 to a 3-volt negative source 108, and through a rectifier 109 and resistor 110 shunted by a capacitor 111 to the negative terminal of the source 63. Rectifiers 107 and 109 are directed to be conducting when the emitter electrode is less negative than 3 or 15 volts, respectively. The emitter electrode is also connected to a conductor 112 leading to the counter 12 (Fig. 1).

In the initial condition, the crystal triode 102 is "on," and all the electrodes are substantially at -15 volts. When a positive trigger pulse arrives from the generator 4 (Fig. 1) over conductor 6, it causes a practically instantaneous rise in the base potential above -15 volts and a corresponding rise in the emitter potential also begins, but on account of the capacitor 111, the rate of rise of the emitter potential is relatively slow. The potential of the base electrode rises to ground potential where it is held by the rectifier 105 which is connected to ground over conductor 40 and the secondary winding of the transformer 99 (see Fig. 5). Because the emitter electrode potential is held negative by the capacitor 111, the rising of the base electrode to ground potential cuts off the emitter current, and when the triggering pulse has disappeared, the crystal triode 102 remains cut off with the base electrode at ground poten-

tial and the emitter electrode potential rising from -15 volts at a rate determined chiefly by the time constant of the elements 103, 110 and 111. The rise of emitter potential continues until it reaches -3 volts where it is held by the source 108. The crystal triode therefore remains cut off. For this circuit to operate correctly, it is necessary that the rate at which the emitter potential can rise should be less than the rate of rise of the leading edge of the triggering pulse, but the time constant of the elements 103, 110 and 111 should be as small as possible consistent with this requirement in order that the emitter potential may reach -3 volts without undue delay.

The change in potential of the emitter electrode between -15 and -3 volts when the crystal triode is triggered "off" as just described is communicated to the counter 12 (Fig. 1) over conductor 112 and releases it in the manner explained.

In order to trigger the crystal triode 102 "on" again, a negative pulse is applied from counter 14 (Fig. 1) over conductor 40 through rectifier 105. This unblocks the crystal triode by reducing the base potential below the potential at which the emitter electrode is held (-3 volts) and all the electrodes then resume potentials near to -15 volts. The sudden fall in base potential is communicated over conductor 21 to the false start reset circuit 17 (Fig. 1) and is differentiated by the elements 93, 95 (see Fig. 4) to produce the short negative pulse required for triggering the crystal triode 86. The corresponding short positive pulse produced by triggering "off" the crystal triode 102 (Fig. 6) will be blocked by the rectifier 94 (Fig. 4), and so will have no effect.

As already explained, the crystal triode 102 is sometimes triggered from "off" to "on" by negative pulses from the counter 13 (Fig. 1) arriving over conductor 84, which is connected to the base electrode of the crystal triode 102 through the gate 19 and conductor 106. The gate 19 comprises four rectifiers 113, 114, 115 and 116, the same electrode of each being connected to a common point which is connected through a resistor 117 to the negative terminal of the source 63. The rectifiers are so directed that all will conduct if a sufficiently large negative potential is applied to the common point. The rectifiers 113 and 114 are connected in series between the conductors 106 and 84. A conductor 118 from the space conductor 3 (Fig. 1) is connected through the rectifier 115 to the common point, and a conductor 119 from the secondary reset device 16 (Fig. 1) is connected through the rectifier 116 to the common point.

At the termination of a false start signal, relay 1 (Fig. 1) is in the marking position, and accordingly conductors 3 and 118 will be at approximately -15 volts. At the same time the secondary reset device 16 (Fig. 1) will be blocked by the ground potential from the mark conductor 2 and so it cannot be triggered "off" by the first timing pulse from counter 13. It therefore applies approximately -15 volts to the gate 19 (Fig. 6) over conductor 119. The common point of the four rectifiers is initially held at ground potential over conductor 84, so both rectifiers 115 and 116 are blocked, the gate 19 is open, and the negative pulse which is generated by the transformer 83 (Fig. 4) at the same time as the first timing pulse will therefore trigger the crystal triode 102 (Fig. 6) "on." The gate 19 will be shut, however, if there is ground potential on either or both of the conductors 118 and 119, because in that case the common point of the four rectifiers is held at ground potential and so the crystal triode 102 cannot be triggered "on."

At the termination of a normal start signal element the gate 19 will be held shut by the ground potential on conductor 118, and the triggering "off" of the secondary reset device 16 (Fig. 1) will apply ground potential over conductor 119 thus holding the gate shut thereafter, whether the relay 1 is on mark or space. Thus any

negative pulses applied over conductor 84 cannot reach the primary reset device 15 to trigger it "on."

It will be seen that the gate 19 is only open during the period between the termination of the false start signal element at 22A (Fig. 2 graph B) and the end 22 of the normal start element period.

The circuit of the short stop corrector 18 of Fig. 1 is shown in the dotted outline designated 18 in Fig. 6. It comprises a crystal triode 120 having the base electrode connected to ground through a rectifier 121 and to the positive terminal of the source 61 through a resistor 122. The rectifier 121 is directed so that it conducts when the base electrode is positive to ground. The emitter electrode is connected through a small current-limiting resistor 123 to the junction point of an adjustable resistor 124 and a capacitor 125 connected in series between the positive terminal of the source 61 and the negative terminal of the source 63. The conductor 42 leading from the counter 14, Fig. 1, is connected to the collector electrode of the crystal triode 120. Normally the crystal triode 120 is "on" and all the electrodes are at potentials near -15 volts because the conductor 42 is normally at -15 volts (see Fig. 5). The base electrode is connected through a rectifier 126 to the junction point of elements 109 and 110 of the primary reset device 15, and rectifier 126 will be blocked when the crystal triode 120 is "on." The capacitor 125 will be practically discharged in this condition. When a positive triggering pulse arrives over conductor 42, it will cut off the crystal triode 120 by cutting off the collector current, and will raise the base electrode substantially to ground potential where it will be held by the rectifier 121, which will now be maintained unblocked by the current through the resistor 122. The capacitor 125 prevents the emitter electrode from immediately rising to ground potential, similarly as described for the crystal triode 102, so that the emitter current of the crystal triode 120 will remain "off" after the disappearance of the triggering pulse. The capacitor 125 starts to charge through the resistor 124 and the potential of the emitter electrode then rises at a rate chiefly determined by the time constant of elements 124 and 125 until it reaches ground potential, when the crystal triode 120 becomes unblocked and assumes the "on" condition with all electrodes again at about -15 volts.

The base electrode thus generates a positive substantially rectangular pulse (43, graph E, Fig. 2) whose duration can be varied by adjusting the resistor 124. During the period of the generated pulse 43 the base electrode is at ground potential and unblocks the rectifier 126. The junction point of elements 109 and 110 is now held substantially at ground potential, and this blocks the rectifier 109 (since the emitter electrode of the crystal triode 102 is at -15 volts when the latter is "on"). The blocking of the rectifier 109 effectively disconnects the capacitor 111 from the emitter electrode of the crystal triode 102, and so the latter now cannot be triggered to "off" by a negative pulse applied over conductor 40, because the emitter electrode can now rise in potential with the leading edge of the pulse, and the crystal triode 102 does not remain cut off on the disappearance of the triggering pulse.

The circuit of the secondary reset device 16 (Fig. 1) is the same as that of the device 15 shown in Fig. 6, in which the short stop corrector 18, the gate 19 and the conductor 21 are now supposed to be omitted. Conductor 6 is replaced by conductor 82 leading from the counter 13 (Figs. 1 and 4); conductor 112 is replaced by the conductor 100 leading to the counter 14; and the rectifier 126 is connected to conductor 2 (Fig. 1) instead of to the short stop corrector 13.

The conductor 119, which leads from the secondary reset device 16 to the gate 19 (Figs. 1 and 6) and has no equivalent in the primary reset device 15, is connected to a tapping point on the resistor 103, as shown

dotted in Fig. 6. This tapping point is chosen so that when the crystal triode 102 is "off," the potential applied to conductor 119 is substantially equal to ground potential, instead of to -3 volts, which is required for conductor 112 or 100.

It was explained above, when the operation of the gate 19 was described, that conductor 119 must be at ground potential for blocking the rectifier 114.

Fig. 7 shows details of the flip-flop devices 9 and 10 of Fig. 1. The arrangement comprises two similarly connected crystal triodes 127, 128 the emitter electrodes of which are connected through equal individual resistors 129, 130 and a common resistor 131 to the positive terminal of the source 61. The base electrodes are connected to ground through rectifiers 132, 133 and to the conductor 82 which leads from the counter 13 (Fig. 1 or 4) through rectifiers 134, 135. Those rectifiers are connected so that they would all conduct if the conductor 82 were positive. The collector electrodes are connected through respective windings of the relay 8 to the negative terminal of the source 63. Rectifiers 136, 137 shunt the windings of the relay and are directed so that the potential of the collector electrodes cannot go below -15 volts. The emitter electrodes are also connected to the negative terminal of the source 63 through rectifiers 138, 139 and resistors 140, 141 shunted by capacitors 142, 143. Conductors 3 and 2 (also shown in Fig. 1) are connected through rectifiers 144, 145 to the junction points of elements 138, 140 and 139, 141 respectively. The base electrodes are connected to the positive terminal of the source 61 through resistors 146 and 147.

The circuits of crystal triodes 127 and 128 correspond respectively to the flip-flop devices 9 and 10 of Fig. 1. When the regenerative repeater is in the marking condition, the crystal triode 128 is "on," with all electrodes at potentials near -15 volts and a relatively large collector current. Crystal triode 127 is "off," with the base electrode at ground potential and the emitter at a negative potential of about 3 volts as determined by the resistors 129, 131 and 140, so that the collector current is very small. The two windings of the relay 8 are so connected in series with the two collector circuits that the collector currents produce opposing fluxes in the relay core. In the marking condition the collector current of crystal triode 128 predominates and operates the moving contact spring of the relay 8 to the position shown.

The connections of the emitter electrodes will be seen to be substantially the same as those of the emitter electrode the crystal triode 102 of Fig. 6, and the circuits 50 behave in the same way because in the marking condition there is ground potential on the conductor 2, the crystal triode 128 cannot be triggered "off" by a timing pulse arriving over conductor 82 because the capacitor 143 is effectively disconnected by the blocking of the rectifier 139. The pulse also can have no effect on the crystal triode 127 which is already "off." However, if relay 1 (Fig. 1) changes over to the spacing condition, conductor 2 will be at a potential of -15 volts, and now capacitor 139 is unblocked and the capacitor 143 55 is effectively reconnected. The timing pulse raises the potential of the base electrode of the crystal triode 128, and the potential of the emitter electrode attempts to follow, but is delayed by the charging of the capacitor 143, as before described, so the crystal triode 128 is left 60 in the "off" condition or the disappearance of the timing pulse, with the base electrode at ground potential and the emitter electrode at about -3 volts, and a very small collector current. The cutting off of the emitter current when the crystal triode is 128 is triggered "off" raises 65 the potential of the conductor 20 connecting the upper ends of resistors 129 and 130, and this triggers "on" the crystal triode 127 by unblocking the emitter contact. It is to be noted that after the relay 1 (Fig. 1) has changed over to the spacing condition, conductor 3 70 is at earth potential, and this effectively disconnects the 75

capacitor 142 so that the potential of the emitter electrode of the crystal triode 127 is not prevented from rising quickly. After the crystal triode 127 is triggered "on" the three electrodes resume potentials near -15 volts and a relatively large collector current flows. The relay 8 is therefore also changed over to the spacing condition, so that a positive potential is now applied to conductor 7. It will be clear from the explanation already given that the flip-flop circuit will be changed back to the marking condition with crystal triode 128 "on" and crystal triode 127 "off" by the first timing pulse which arrives after the relay 1 (Fig. 1) has changed back to the marking condition.

It will be understood that while Figs. 3 to 7 give practical examples of crystal triode circuits for the elements of Fig. 1, various other circuits are possible for carrying out similar functions.

It should also be understood that the invention is not restricted to regenerative repeaters for start stop systems, but is applicable to other binary code systems, such as the Baudot multiplex system, which employ a succession of signal elements separated by transitions. In such systems the start-stop arrangements are usually replaced by synchronising means whereby synchronising signals are periodically transmitted with the code signals for maintaining the receiver in step with the transmitter. The arrangements described with reference to Fig. 1 will of course need modification for such a system, and such modification can readily be made by anyone skilled in the art when the conditions which have to be met are specified. The counting chain employing crystal triodes such as that shown in Fig. 1 will be synchronised or controlled by the synchronising signals.

While the principles of the invention have been described above in connection with specific embodiments, and particular modifications thereof, it is to be clearly understood that this description is made only by way of example and not as a limitation on the scope of the invention.

What I claim is:

1. An electric telegraph regenerative repeater for start-stop code combinations of signal elements comprising a master oscillator, a crystal triode counting device controlled thereby for generating a train of short timing pulses having a repetition period equal to a signal element period, said counter device being normally inoperative, starting means operated in response to a start transition for rendering said counter device operative, terminating means operative upon the lapse from the commencement of a retransmitted start element of a period at least equal to the combined durations of said start element and the code combination immediately following for rendering said counter device again inoperative and a flip-flop device for retransmitting the received signal elements under control of said timing pulses.

2. A repeater according to claim 1 in which the said starting means comprises a first two-condition trigger device adapted to apply a blocking potential to the said counter device or part thereof, means for generating a short trigger pulse in response to each received transition, and means for applying the trigger pulse generated in response to the start transition to trigger the said first trigger device to the opposite condition in such manner as to remove the blocking potential, thereby rendering the said counter device operative.

3. A repeater according to claim 2 in which the said terminating means comprises a second counter device operated by the said first counter device and adapted to generate a short terminating pulse shortly after the receipt of the stop transition, the said terminating pulse being applied to restore the said first trigger device to the first condition thereby re-applying the blocking potential to the said first counter device.

4. A repeater according to claim 3 in which the said second counter device is normally held inoperative by a blocking potential derived from a second two-condition trigger device when in a first condition, and in which the first timing pulse following upon the start transition is applied to trigger the second trigger device to the second condition whereby the blocking potential is removed from the second counter device thereby rendering it operative.

5. A repeater according to claim 4 in which the said terminating pulse is applied to restore the said second trigger device to the first condition, thereby reblocking the second counter device and rendering it again inoperative.

6. A repeater according to claim 5 further comprising inhibiting means for preventing the said repeater from responding to a false start element whose duration is less than half an element period.

7. A repeater according to claim 6 in which the said inhibiting means comprises means for examining the incoming signal condition at the time of the first timing pulse following upon a start transition, means responsive to that condition being then marking for preventing the said flip-flop device or the second trigger device from being triggered, and means for applying a pulse from the said counter device to restore the first trigger device to the first condition, thereby rendering the said counter device again inoperative.

8. A repeater according to claim 7 in which the last-mentioned pulse is applied to the first trigger device through a gate circuit, comprising means for applying blocking potentials to the said gate circuit during the period following a start transition in which a spacing condition is being received and also during the period when the second trigger device is in the second condition.

9. A repeater according to claim 1 wherein said crystal triode counting device comprises a first series of crystal triode trigger circuits connected to said master oscillator to produce an output pulse upon every nth cycle of said oscillator and a second crystal triode trigger counting device connected to said first series to produce an output pulse upon every nth pulse from the output of said first series, means responsive to a start transition to render the connections of said first series to said oscillator effective and to render said second counting device effective to produce a pulse upon the first pulse from said first series.

10. A repeater according to claim 9 further comprising delaying means for preventing the first trigger device from being triggered to the second condition for a specified period after the receipt of the stop transition.
